JOHN M. STRUZAS AND JOHN KULLUK, OF ROCKFORD, ILLINOIS.

POTATO-PARING MACHINE.

1,304,716.

Specification of Letters Patent. Patented May 27, 1919.

Application filed September 13, 1917. Serial No. 191,134.

To all whom it may concern:

Be it known that we, JOHN M. STRUZAS and JOHN KULLUK, citizens of Russia and the United States, respectively, both residing at Rockford, in the county of Winnebago and State of Illinois, have invented certain new and useful Improvements in Potato-Paring Machines, of which the following is a specification.

10 This invention relates to the paring or removal of the skins of potatoes and other vegetables, and the primary object of our invention is to provide an improved machine, by means of which a quantity of potatoes or other vegetables may be quickly and easily pared by a mechanical agency, thus obviating the tedious and often wasteful task of paring such vegetables by hand.

Another object of our invention is to provide a paring machine of the character described, which shall be especially adapted to be used in hotels, restaurants and other places where potatoes and similar vegetables are used in large quantities.

25 We have also aimed to provide a paring machine of such improved construction that it may be produced at a comparatively low cost and which will perform the paring operation in a very satisfactory and efficient manner.

30 Referring to the drawing:

Figure 1 is a vertical sectional view through a paring machine embodying our improvements; and

35 Fig. 2 is a plan view of the machine, partly in section.

In this invention we have contemplated, generally stated, the provision of a container in which is disposed a revoluble cylindrical 40 hopper having an oppositely revoluble bottom, the interior wall of the hopper and its bottom having an abrasive surface, so that when the hopper and its bottom are simultaneously revolved in opposite directions by 45 means of a simple operating mechanism, and water is supplied or sprayed onto potatoes in the hopper, the potatoes will be tumbled and rubbed against the abrasive surfaces of the hopper and its bottom and thereby pared.

50 The container designated generally by reference character 3, may be of any suitable construction, and as shown, is of cylindrical form, covered with a sectional top, one portion 4 of which serves as a permanent closure, and the other section 5 as a movable 55 closure, allowing access to the interior of the

container for the insertion and removal of potatoes or other vegetables. Within the container is revolubly mounted a cylindrical hopper designated generally by character 6. 60 This hopper revolves about an upright axis and is preferably mounted upon and sustained directly by the circular walls of the container 3, a substantial distance above the bottom of the latter so that the mounting 65 will be disposed above the water and parings, which drain into the bottom of the container. An annular track 7 is, therefore, secured to the interior wall of the container above its bottom, as shown, and the hopper 70 is equipped with a plurality of rollers 8 riding on the track, the rollers and track constituting the agency through which the hopper is revolubly mounted on the container. An inwardly and downwardly tapering splash 75 plate or guard 9 may be secured to the lower portion of the hopper, as shown, for keeping the trackway in a clean condition by deflecting the falling water and refuse or parings inwardly away from the track. The hopper 80 is guided and steadied at its upper end against lateral displacement by means of a plurality of rollers 11, mounted on the container and engaging an annular peripheral track 12 formed integral with a channel casting 85 13 secured to the top of the hopper and provided on its upper surface with an annular rack face 14. Means, presently mentioned, is adapted to revolve the hopper through the agency of a gear meshing with 90 the rack 14. An upright shaft 15 revolubly mounted on the container centrally therein, is equipped with a platform 16, disposed within the hopper, as shown, and constituting the bottom thereof. The interior wall of 95 the hopper and the top of the platform 16 is provided with a suitable roughened or abrasive surface 17 adapted by its contact with the potatoes or other vegetables to pare the same. Such surface may be formed of sheet 100 metal perforated very finely in such manner that roughened edges of the perforations project inwardly and constitute the abrasive surface. This construction, however, is not essential since any suitable or preferred 105 abrasive surface might be employed for the purpose. Means are provided for simultaneously revolving the hopper 6 and the bottom 16 thereof in opposite directions comprising a horizontal drive shaft 18 suitably mounted on the top on the container, in this 110 instance, in bearings 19 and 21, secured to

- the container, and gearing between this drive shaft 18 and the shaft 15 and rack 14. This gearing consists of bevel gears 22 between the shafts 15 and 18 and the gears 23 and 24 5 between the shaft 18 and rack 14, the gear 24 being a small intermediate gear mounted on the top 4 of the container and serving to reverse the direction of the drive of the shaft 18 so that the hopper 6 will be revolved oppositely to the direction of rotation of the hopper bottom 16. In the present construction, the upper end of the shaft 15 is journaled in a bearing integral with the bearing bracket 19, although this construction might 10 be changed or modified if desired. While the present machine is equipped with a hand crank 25 attached to a fly wheel secured to the outer end of the shaft 18, power operated means might be equally well applied to the shaft 18 for driving the same. Suitable means is provided for spraying or otherwise supplying and distributing water over the top of the potatoes or other vegetables for cleaning the same. This means may be in 15 the form of a spray nozzle 26 having a supply hose 27 passing through the top 4 of the container. The water draining through the bottom of the container may be removed therefrom through the outlet 28, which is 20 provided with a suitable valve. In this instance, the top of the container is provided with a hinged cover, mentioned above, which affords an entrance to the hopper. 25 In the operation of our improved potato paring machine, the potatoes or other vegetables are placed in the hopper through the opening in the top thereof. The paring operation takes place when the drive shaft 18 is revolved either by hand or power, as may 30 be desired, thus causing the hopper 6 and

bottom 16 thereof to be simultaneously revolved in opposite directions and causing the potatoes to be moved about and agitated in the hopper, and in the course of their movement to be rubbed against the abrasive surfaces of the hopper and its bottom, and to be thereby pared. After the potatoes have been pared, they may be cleansed by water from the spray nozzle 26 and removed through the top of the container. This mechanism provides a simple device for paring quantities of potatoes and other vegetables and does not in its manufacture entail a large cost such as might make its use prohibitive. The machine may be operated very easily, either by hand or power, thus being adapted for all conditions of usage. While we have shown and described a single working embodiment of our improvements, it should be understood that various changes in the construction and arrangement of parts might be made without departing from the spirit and scope of the invention as expressed in the appended claim. 45 50 55 60 65

We claim:

A machine of the character described comprising a cylindrical container having an annular track about its interior wall, a cylindrical open-end hopper mounted on and supported by said track so as to revolve within the container, a central upright shaft revolvably mounted in the container at the top and bottom thereof and equipped with a platform constituting the bottom of the hopper, and common means for actuating the shaft and the container in opposite directions. 70 75

JOHN M. STRUZAS.
JOHN KULLUK.
